(57) **CLAIM**

The ornamental design for a diffuser, as shown and described.

DESCRIPTION

FIG. 1 is a top perspective view of a diffuser, showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view thereof of another embodiment;

FIG. 10 is a bottom perspective view thereof of another embodiment;

FIG. 11 is a front view thereof of another embodiment;

FIG. 12 is a rear view thereof of another embodiment;

FIG. 13 is a left side view thereof of another embodiment;

FIG. 14 is a right side view thereof of another embodiment;

FIG. 15 is a top view thereof of another embodiment;

FIG. 16 is a bottom view thereof of another embodiment;

FIG. 17 is an enlarged detail view of area 17 in FIG. 1;

FIG. 18 is an enlarged detail view of area 18 in FIG. 1;

FIG. 19 is an enlarged detail view of area 19 in FIG. 9; and,

FIG. 20 is an enlarged detail view of area 20 in FIG. 9.

The broken lines in the drawings illustrate the portions of the diffuser, which form no part of the claimed design.

The dash-dot-dash broken lines encircling the enlarged views are for annotative purposes only and form no part of the claim thereof.

1 Claim, 20 Drawing Sheets
